Geo. S. Wheelock
ATTORNEY

UNITED STATES PATENT OFFICE.

WALTER F. GEMEINHARDT, OF NEW YORK, N. Y., ASSIGNOR TO THE WOODWIND COMPANY, OF NEW YORK, N. Y., A FIRM COMPOSED OF EUGENE BERCIEUX AND WALTER F. GEMEINHARDT.

SAXOPHONE.

Application filed October 16, 1925. Serial No. 62,795.

This invention relates to improvements in musical wind instruments and has particular reference to saxophones.

In rendering a musical selection on a saxophone, the musician blows into the instrument, and at the same time, manipulates a number of fingerpieces for different sound-producing valves, the skill of the performer depending largely upon the dexterity of his fingers. It has been known to those skilled in the art, that the highest notes have been the most difficult to produce, and that with standard saxophones the high "F" note is practically impossible to produce accurately by manipulation of the fingerpiece and valve provided for it. When the "F" valve is relied upon to obtain the high "F", the note seems to be damped or suppressed, is not clear or accurate, and is somewhat off pitch. This tendency has been overcome by some performers by operating certain other valves simultaneously with the "F" valve to compensate for the error. Such manipulation requires great skill, necessitating the use of fingers on both hands. In some selections, due to the arrangement of the notes, it is impossible even for the most expert performers to accomplish such a combination, and less skilled players cannot do it at all. With my invention I overcome those difficulties and objectionable features of the prior art by providing mechanism whereby certain independently operated valves may be simultaneously operated when desired.

An object of the present invention is to provide a saxophone with means for readily producing a clear and true high "F" note by manipulation of a single fingerpiece.

Another object is to provide such a device which will be conveniently located and supplementary to the usual fingerpieces provided in instruments of this character.

With these and other objects in view, the invention resides in the novel features of construction, combination, and arrangement of parts hereinafter set forth, illustrated in the accompanying drawings, and specifically pointed out in the appended claims.

In the drawings, Fig. 1 is a front elevation of a portion of a saxophone with my invention applied thereto;

Fig. 2 is a transverse sectional view, on the line 2-2 of Fig. 1, showing two of the valves closed;

Fig. 3 is a view similar to Fig. 2 with the valves open;

Fig. 4 is a longitudinal sectional view on the line 4-4 of Fig. 1, with parts in operated position.

The invention is applicable to any standard saxophone comprising a horn or tube 10 having a plurality of ports 11 in its side, and fitted at its upper end with a mouth-piece 12. The ports 11 are of various diameters, and so spaced from the mouth-piece 12 that each port will control or produce a different note of the musical scale, the highest notes of the scale range being uppermost on the horn 10. Each port is fitted with a valve comprising a disc 13 preferably formed of metal, and carrying on its inner surface a cushioning member 14 of suitably resilient material to provide an air tight seal when seated against the mouth of the port.

The uppermost valve, designated by the letter F, is designed to control the production of the high "F" note, and is normally closed. In order that this valve may be operated, it is attached to one end of a lever 15 which is pivoted at 16, and provided at its other (lower) end with a fingerpiece 17. Thus, depression of the fingerpiece 17 opens the valve "F", and in order to prevent lateral displacement, the lever 15 is guided in a bifurcated post 18 on the side of horn 10.

Disposed slightly below the valve "F", and to one side thereof, is a similar valve "E" which is also normally closed, and is carried on a rocker-arm of a shaft 20 which extends longitudinally of the tube 10, and pivotally supported in bearing brackets 21. Adjacent its lower end, the shaft 20 is equipped with a key or fingerpiece, not shown, by which the valve "E" may be actuated. Other valves "D", "C", "B", and "A" are disposed substantially as shown, each being adapted to control the high note of a corresponding designation. The valves "D" and "C" are normally closed, and are operable by depression of pivoted fingerpieces 22 and 23, respectively.

The valves "B" and "A" are normally opened and supported by rocking arms 24 and 25, respectively, carried by a pivot rod 26 which extends parallel to the pivot rod 20. The disk 13 of valve "A" is provided with a suitable finger engaging surface 27 by which it may be operated to close the corre-

sponding port in the tube 10. In playing the instrument, the performer arranges the fingers of his left hand in proximity to the finger pieces 17, 22, 23 and 27 and, as will be understood, the various notes may be obtained by proper manipulation of said fingerpieces while blowing into the instrument. A number of other valves similar to those illustrated and described are disposed further down upon the tube 10, said valves having suitable operating means for engagement by the fingers of the right hand.

In most instances when the fingerpieces 17 are depressed to open the valve "F" a clear high "F" note is not produced and, as has been previously stated, experts have found it necessary in order to clear up the tone of said note, to simultaneously open the valve "E" and to close the valves "B" and "A". The "F" and "A" valves are operated by fingers of the left hand, while the "E" valve is operated by a finger of the right hand and, due to the arrangement of the parts, this is very difficult of accomplishment because of the fact that the fingers of the right hand must ordinarily be maintained adjacent to the other series of valves at the lower end of the tube 10.

In order to facilitate the simultaneous operation of the four valves specifically mentioned in the preceding paragraph, I provide a pivoted lever 28 supported on a pivot 29 on the side of the tube 10, as best shown in Figs. 1 and 4. The upper end of the lever 28 has a transverse arm 30 which engages at one side an extension 31 of the lever 15, and at its other side a lug 32 secured to the disk 13 of valve "E". The lower end of the lever 28 is outwardly curved and suitably widened, as at 33, to form a convenient fingerpiece, and carries on its inner surface a cushioning member 34, which engages the outer surfaces of the valves "A" and "B". Thus, it will be seen that as the lever 28 is rocked about its pivot 29, it will open the valves "E" and "F" by virtue of its engagement with the lug 32 and projection 31, and at the same time it will close valves "A" and "B".

By this arrangement the necessary valves may be operated to produce a clear high "F" note by the use of a single finger of the left hand of the performer, and the means for accomplishing this result are conveniently located so that the performer need not move

his left hand away from the vicinity of the other left hand fingerpieces.

From the foregoing, it will be apparent that each of the valves may be independently operated by the standard mechanism provided for the purpose, and that, when desired, certain of the valves may be simultaneously operated by the new fingerpiece forming the subject-matter of this invention.

It is obvious that this invention is susceptible to modification and that such modification may be resorted to by skilled mechanics without departing from the spirit and scope of the invention as expressed in the appended claims.

What I claim as my invention and desire to secure by Letters Patent of the United States is:

1. In a saxophone, in combination, a horn, a pair of normally closed valves in laterally offset relationship, a pair of normally open valves, extension lugs carried by each of the normally closed valves, means for operating each of the valves independently, and additional means for operating said valves simultaneously, said additional means comprising a lever pivotally mounted on the horn between the two pairs of valves, said lever having a transverse arm at one of its ends underlying the extension lugs of both of the normally closed valves, and the opposite end of the lever forming a finger-key, engaging both of the normally open valves.

2. In a saxophone, in combination, a horn, a pair of normally closed valves in laterally offset relationship, a pair of normally open valves, extension lugs carried by each of the normally closed valves, means for operating each of the valves independently, and additional means for operating said valves simultaneously, said additional means comprising a lever pivotally mounted on the horn between the two pairs of valves, said lever having a transverse arm at one of its ends underlying the extension lugs of both of the normally closed valves, the opposite end of the lever being widened to form a finger-key, and the inner surface of said finger-key being provided with a cushioning member for engaging both of the normally open valves.

In testimony whereof I have hereunto affixed my signature.

WALTER F. GEMEINHARDT.
